US00D611928S

(12) **United States Design Patent**
Hansen et al.

(10) **Patent No.:** US D611,928 S
(45) **Date of Patent:** ** Mar. 16, 2010

(54) **WIRELESS HOME AUDIO DEVICE**

(75) Inventors: **Eskild Timme Hansen**, Copenhagen OE (DK); **David Gresham**, East Hampton, NY (US)

(73) Assignee: **Cisco Technology, Inc.**, San Jose, CA (US)

(**) Term: **14 Years**

(21) Appl. No.: **29/325,415**

(22) Filed: **Sep. 30, 2008**

(51) **LOC (9) Cl.** 14-03

(52) **U.S. Cl.** D14/188

(58) **Field of Classification Search** D14/137, D14/138, 155, 160-171, 188, 189, 193-198, D14/204, 207, 213, 214, 217, 265, 299, 496; D13/107, 108, 118; 455/90.1-90.3, 344-355, 455/899; 369/6-12; 370/342-344

See application file for complete search history.
